UNITED STATES PATENT OFFICE.

EDWARD H. AMET, OF CHICAGO, ILLINOIS, ASSIGNOR TO H. A. STREETER,
OF SAME PLACE.

BRUSH-SHIFTER FOR DYNAMO-ELECTRIC MACHINES.

SPECIFICATION forming part of Letters Patent No. 340,539, dated April 27, 1886.

Application filed January 28, 1886. Serial No. 190,030. (No model.)

To all whom it may concern:

Be it known that I, EDWARD H. AMET, a citizen of the United States, residing in Chicago, in the county of Cook and State of Illinois, have invented a new and useful Improvement in Brush-Shifters for Dynamo-Electric Machines, of which the following is a specification.

My invention relates to certain improvements in brush-shifters of dynamo-machines for regulating the current generated.

In my invention the position of the collecting-brushes of the generator is automatically regulated or adjusted by means of a controlling-magnet included in the circuit to be regulated, which operates as a relay to open and close circuits in which two electro-magnets are included. One of these latter magnets operates to tilt a rocking lever in one direction, and move a constantly-driven gear or friction wheel into connection with a similar gear or friction wheel on the shaft which carries the pulley for shifting the brushes. The other of these two magnets, when the circuit is closed through the same, operates to tilt the rocking lever in the opposite direction, and in a similar manner give an opposite movement to the brushes of the generator. When the circuit through both these magnets is open, the rocking lever stands in a horizontal or normal position, so that both the gears on the rocking lever remain out of connection with the gear on the shaft of the brush-shifting pulley.

My invention also consists in the novel devices and combinations of devices herein shown and described, more particularly pointed out in the claims.

In the accompanying drawings, which form a part of this specification, and in which similar letters of reference indicate like parts, Figure 1 is a side elevation of a device embodying my invention, showing also a diagram of the circuit-connections. Fig. 2 is a plan view of the rocking lever and its operating-magnets, and Fig. 3 is a rear view of the same; and Fig. 4 is a section of the friction-pulley, through which the power is communicated to the brush-ring.

In said drawings, A represents a dynamo-machine, which may be of any suitable or ordinary construction, A' A' its collecting-

brushes, and A² the external circuit, the current on which is to be regulated.

B represents a controlling or relay magnet included in the main circuit A², either directly or in a shunt or branch circuit, B', connected therewith. Where the device is used with an incandescent-light mechanism, the magnet B should be included in a branch, B'; but where the apparatus is used on an arc-light mechanism the magnet B should be connected in series on the main circuit.

D and D' are two electro-magnets, which are normally open circuited, and which operate the tilting lever E in one direction or the other, according as the circuit is closed through magnet D or D'. This tilting lever E carries two constantly oppositely-driven friction-wheels, e e'. These friction-wheels e e' may be constantly driven in opposite directions in any suitable manner, but preferably by intermeshing gears e² e³ on the shafts of said friction-wheels, one of which gears, e², is driven by a gear, e⁴, on the stud or shaft e⁵ of the driving-pulley e⁶. This driving-pulley may receive its motion from any moving part on the dynamo-machine, or of the engine by which the same is driven.

On a suitable standard, F, is journaled a shaft, f, which carries on one end a friction-wheel, f', which engages one or the other friction-wheels, e e', according as the lever is tilted in one direction or the other. When the lever E remains in its normal or horizontal position neither of the friction-wheels e e' engage the friction-wheel f'. On the front end of the shaft f a sprocket-wheel or pulley, f², is provided, which communicates with the brushes A' A', or their rotary carrier, by means of a sprocket-wheel, chain, or band, f³. The sprocket-wheel f² is preferably not keyed rigidly to the shaft f, but is connected thereto by means of a double friction ring or clamp, f⁴, or other suitable friction device, so that the pulley or sprocket-wheel f² may give or yield when necessary, and thus prevent strain upon the mechanism after the brushes reach the limit of their movement.

The relay-magnet B is provided with a movable armature-switch lever, b, which operates to close the circuit through the magnet D or the magnet D', according as said switch is

brought in contact with the contact-piece b' or the contact-piece b^2 . A spring, b^3 , and its adjusting-screw b^4 , serve to hold the switch b out of connection with both the contact-points b' or b^2 when the normal or proper amount of current is flowing through the circuit.

A wire, G, leads from the contact-piece b' through the magnet D to the binding-post N, which is connected to the main circuit by a wire, n, and a wire, H, leads from the contact-piece b^2 through the magnet D' to the binding-post N.

In operation, when the current on the circuit A³ is at its normal or proper amount the switch or armature-lever b of the relay-magnet will occupy an intermediate position between the contact-points b' and b^2 , and thus both the magnets D and D' will remain out of circuit. When for any cause the current on the circuit A² exceeds its proper strength, the relay-magnet B will move the switch b into connection with the contact-piece b' , and thus close the circuit G through the magnet D, thereby pulling that end of the rocking lever E down, so that its constantly-revolving friction-wheel e engages the friction-wheel f' on the pulley-shaft f , and causes said shaft and pulley to rotate in the direction necessary to move the brushes A' A' to diminish the amount of current generated. This movement of the brushes A' A' will continue until the normal strength of the current is restored, when the armature of the relay-magnet will resume its normal or central position, and thus cut out the magnet D, when the shaft f will of course cease rotating. When, on the other hand, the current falls below its normal or proper amount, the relay-magnet B being thereby weakened, its armature b will be thereby pulled into connection with the contact-point b^2 by the spring b^3 , thus closing the circuit through the opposite magnet, D', and thereby causing the shaft f and the brushes A' A' to rotate in the opposite direction, and thus increase the amount of current generated until the normal or proper current strength is restored, when the relay B will again cut out the magnet D'. By this means, as power for shifting the brushes A' A' is furnished by the constantly-driven gears, and as the friction wheels or gears are moved in and out of contact by the magnets D and D', which are normally out of circuit or short-circuited, the controlling-magnet B has no work to do, except to open and close the circuits through the magnets D and D', and therefore the regulator is and can be readily made extremely sensitive and quick to respond to very slight changes in the current, and consequently the current will be maintained practically and constantly at its proper amount.

My regulator mechanism is so delicate that it will respond to so slight a change as that caused by the extinguishment, for example, of one incandescent lamp out of a great number connected in multiple arc, or permit all the incandescent lamps but one to be extinguished without injury to the remaining lamps; and

incandescent lamps and arc lamps may also be run on the same circuit.

My regulator is so delicate and sensitive that it will readily respond to a very slight change in the current—as, for example, that of one-tenth of an ampère.

The constantly-driven gear e^4 , which communicates motion to the gears e^3 e^2 on the tilting lever E, will have a tendency to tilt the lever, especially when one of the friction-wheels, e or e' , is pressed against the friction-wheel f' and the brushes are being shifted or moved; but the pull of each of the magnets D D' is sufficient to overcome this opposing force and hold the friction-wheels e or e' and f' together with the requisite pressure. This force operates, of course, in favor of one of the magnets and against the other—that is, it helps magnet D' hold the friction-wheel e against the wheel f' and opposes the magnet D. The magnet D' might therefore be made slightly smaller or weaker than the magnet D; but in practice I make both magnets of the same size, as is shown in the drawings, as the disturbing influence of the gear e^4 on the lever E is comparatively slight in relation to the force of the magnets D D'. When neither of the frictions e or e' are pressed against the wheel f' by the magnets D or D', the friction of the loose gears e or e' or the resistance offered by them to the gear e^4 is so slight that the latter has such a very slight tendency to pull the lever E that it is inappreciable, and whatever tendency there may be is or may be balanced by the adjustment of the lever or of the armatures carried by it. It will of course be understood that this tendency of the gear e^4 to tilt the lever E has no effect whatever upon the sensitivity of the apparatus, as its sensitivity depends entirely upon the delicacy of adjustment of the relay-magnets B, which opens and closes the circuit through the operating-magnets D and D'. The only effect of this tilting tendency of the gear e^4 on the lever E is to require the use of larger magnets D D' than might otherwise be necessary.

I claim—

1. The combination, with a dynamo and its brushes, of a relay-magnet, B, magnets D and D', circuits through which are opened and closed by said relay-magnet, rocking lever E, provided with constantly-driven wheels e and e' , one on each side of its pivot, shaft f , furnished with wheel f' , engaging with one or the other or neither of said wheels e and e' , according as said rocking lever is tilted in one direction or the other or occupies its normal position, and a connection between said shaft f and said brushes, substantially as specified.

2. The combination, with a dynamo and its brushes, of a relay-magnet, B, magnets D and D', circuits through which are opened and closed by said relay-magnet, rocking lever E, provided with constantly-driven wheels e and e' , one on each side of its pivot, shaft f , furnished with wheel f' , engaging with one or the other or neither of said wheels e and e' , ac-

cording as said rocking lever is tilted in one direction or the other or occupies its normal position, wheel f^2 , and chain or band f^3 , connecting said wheel f^2 and said brushes, substantially as specified.

3. The combination, with a dynamo and its brushes, of a relay-magnet, B, magnets D and D', circuits through which are opened and closed by said relay-magnet, rocking lever E, 10 provided with constantly-driven wheels e and e' , one on each side of its pivot, shaft f , furnished with wheel f' , engaging with one or the other or neither of said wheels e and e' , according as said rocking lever is tilted in one 15 direction or the other or occupies its normal

position, wheel f^2 , friction-rings or clamp f^4 , connecting said wheel f^2 to said shaft f , and a chain or band, f^3 , substantially as specified.

4. The combination, with a dynamo and its brushes, of a relay-magnet, B, two magnets, 20 D and D', having a lever or armature furnished with two oppositely-driven wheels, and mechanism for communicating the motion of one or the other of said wheels to said brushes according as said lever is moved in one direction or the other, substantially as specified. 25
